UNITED STATES PATENT OFFICE.

MAX ULRICH, OF EASTHAMPTON, MASSACHUSETTS.

GOVERNOR FOR STEAM-ENGINES.

SPECIFICATION forming part of Letters Patent No. 332,764, dated December 22, 1885.

Application filed October 13, 1885. Serial No. 179,760. (No model.)

To all whom it may concern:

Be it known that I, MAX ULRICH, of Easthampton, in the county of Hampshire and State of Massachusetts, have invented certain new and useful Improvements in Governors for Steam-Engines, of which the following is a specification.

This invention relates to an improved form of governor for steam-engines; and it consists 10 of a governor having oscillating weights pivoted to the web of a pulley on the main shaft, said weights having slotted levers that engage pins of a laterally-sliding governor-box provided with an annular groove and loosely- 15 turning collar, to which a reciprocating rod is attached, which connects with the throttle-valve of the engine, as will appear more fully hereinafter, and finally be pointed out in the claims.

20 In the accompanying drawings, Figure 1 represents a vertical transverse section of a pulley with my improved centrifugal governor. Fig. 2 is an end view of the same, partly in section. Figs. 3 and 4 are details of 25 the sliding governor-box and rotating collar, and Fig. 5 is an end view of the supporting standard of the main shaft, showing the guide-opening for the rod connecting the governor-box with the throttle-valve of the engine.

30 Similar letters of reference indicate corresponding parts.

Referring to the drawings, A represents the main shaft of the steam-engine. F is a fly-wheel applied to the same; B, a pulley that is 35 cast integral with the fly-wheel or attached in a suitable manner thereto. The governor is arranged within the pulley B, and consists of two weights, C C', which are hinged to fixed lugs a a', the square shanks of which are passed

40 through square holes in the common web of the pulley and fly-wheel, said shanks being threaded at the end and secured to said web by screw-nuts b b'. The weights C C' are made of parabolic shape and provided with levers

45 d d', which are guided by slots e e' at their inner ends on guide-pins f f', that are screwed into lugs g' of a laterally-sliding sleeve, g, placed on the shaft S. The weights C C' are connected by spiral springs i i' to screw-eyes 50 l l' of the hub of the pulley B, the outer ends of the springs being passed through holes in

the weights C C', and attached thereto by screw-nuts k k'. The weights C C' are pulled by their springs i i' toward the center of the pulley to such an extent that the outer end of 55 the slots e e' abut against the pins f f', as shown in Figs. 1 and 2.

As soon as the shaft S rotates at a certain speed, the weights C C' are moved by centrifugal force in outward direction, whereby the 60 slots e e' of the levers d d' move along the pins f f' and cause thereby the governor-sleeve g to move outwardly toward the standard R. When the speed is diminished, the weights C C' are drawn by the springs i i' toward the 65 center of the pulley, so that the governor-box is moved in inward direction toward the hub of the pulley B. The oscillating motion imparted to the weights C C' imparts thereby a laterally-reciprocating motion to the governor- 70 sleeve g. The sleeve g is provided with a circumferential groove, g', in which turns a ring-shaped collar, m, that is made of two sections and connected by screws, as shown in Fig. 3. At one side of the ring m is arranged a screw- 75 socket, n, to which is attached a horizontal rod, o, which connects the governor-box g with the throttle-valve of the engine. The rod o is guided in a hole, p, of the standard R, as shown in Figs. 1 and 5, which hole 80 guides the rod o and imparts to the same a rectilinear reciprocating motion, by which the throttle-valve is opened or closed, so that the same responds to the motion of the oscillating weights of the governor. The tension of the 85 spiral springs i i' on the weights C C' are regulated by the screw-nuts k k', which are set into depressions of the weights and provided with milled rims for being conveniently adjusted.

In this manner a centrifugal governor of simple construction and of a high degree of sensitiveness is furnished, that is specially adapted for steam-engines running at high speed.

Having thus described my invention, I claim as new and desire to secure by Letters Patent—

1. The combination of a pulley, B, oscillating weights C C', pivoted to the web of said pulley and provided with slotted levers d d', 100 spiral springs i i', connecting the weights C C' with the hub of the pulley, a laterally-sliding

governor-sleeve, *g*, provided with lugs *g' g'* and pins *ff'*, a ring-shaped collar, *m*, guided loosely in a groove of said sleeve, and a rod, *o*, connecting said collar to the throttle-valve 5 of the engine, substantially as set forth.

2. The combination of a pulley, *B*, having fixed lugs *a a'*, oscillating weights *C C'*, pivoted to said lugs and having slotted levers *d d'*, tension-springs *i i'*, attached at their inner 10 ends to the hub of the pulley and at their outer ends to holes through the weights, adjusting-nuts *k k'*, and a governor-sleeve having lugs *g g'*, and guide-pins *ff'*, for guiding the slotted ends of the levers *d d'*, substantially as set 15 forth.

3. The combination of a pulley, *B*, oscillating weights *C C'*, pivoted to said pulley and having slotted levers *d d'*, tension-springs *i i'*,

connecting the weights with the hub of the pulley, a laterally-sliding governor-sleeve, *g*, 20 having lugs *g' g'* and guide-pins *ff'* for the slotted levers *d d'*, a ring-shaped collar, *m*, guided in a groove of the governor-sleeve and provided with a screw-socket, *n*, and a connecting-rod, *o*, secured to the socket *n*, and 25 guided in an opening, *p*, of the supporting-standard of the main shaft *S*, substantially as set forth.

In testimony that I claim the foregoing as my invention I have signed my name in presence of two subscribing witnesses.

MAX ULRICH.
